UNITED STATES PATENT OFFICE

GEORGE LASKER, OF CHICAGO, ILLINOIS

MARINE BOILER

Application filed May 29, 1931. Serial No. 540,963.

My invention relates to boilers and more particularly it relates to boiler installations designed to carry rapidly changing loads or power requirements. The invention contemplates improvements in boiler construction of the general type described in my co-pending applications, Serial No. 470,359, filed July 24, 1930, and Serial No. 470,609, filed July 25, 1930, wherein the construction provides for maintaining a substantially constant water level at a predetermined elevation above the boiler proper.

An object generally of the invention is the provision of an improved boiler construction comprising a novel arrangement of drums and connecting tubes, adapting the same for use as a marine boiler or for use on other moving objects regardless of the amount of lurching, pitching or plunging of the object on which the boiler may be mounted whereby the water line is maintained at a substantially permanent elevation above the boiler for all of the varied positions of the vessel or other moving object upon which the boiler is mounted and the quantity of steam generated remains unaffected by the listing of the boat or object.

Another object of the invention is the provision of a novel boiler construction comprising drums interconnected by tubes, wherein one of the drums extends vertically a substantial distance above the main boiler portion and is so connected to the boiler at the top and bottom that rapid circulation of the boiler contents automatically results.

A further object of the invention is the provision of a storage drum or cylinder so positioned as to provide a constant pressure head in all portions of the boiler and which provides a potential steam and water capacity adapting the boiler to temporarily carry peak loads of a magnitude several times greater than the normal load for which the boiler is designed.

A still further object of the invention is the provision in boiler construction of a drum of novel construction and arrangement adapting it for use as a receiver, separator, steam and water storage, and also as a means

for separating and removing impurities, both heavier and lighter than water.

Still another object is the provision of novel means for separating water and steam and for separating impurities therefrom.

A still further object is the provision of a novel furnace and boiler construction which permits the maximum possible amount of water cooling in accordance with the furnace volume wherein all parts of the cooling surfaces are constantly supplied with water and thereby prevents the possibility of overheating any portion of the boiler.

Still another object of the invention is the provision of novel means for separating articles both lighter and heavier than water from the boiler contents.

Among further objects of the invention is the provision of a boiler of the kind described, which is simple in construction, which may be readily and conveniently fabricated and assembled, which may be economically manufactured and which, in its construction, assembly and use, provides improvements and conveniences not hitherto employed in the art for the same general purpose.

Many other objects and advantages of the construction herein described and shown will be obvious to those skilled in the art from the disclosure herein given.

To this end my invention consists in the novel construction, arrangement and combination of parts herein described and shown and more particularly pointed out in the claims.

In the drawings, wherein like reference characters indicate like or corresponding parts,

Fig. 1 is a vertical sectional view through a boiler embodying the principles of my invention;

Fig. 2 is a section along the line 2—2 of Fig. 1;

Fig. 3 is a section along the line 3—3 of Fig. 1;

Fig. 4 is a section along the line 4—4 of Fig. 1 drawn to a larger scale;

Fig. 5 is a section along the line 5—5 of Fig. 4; and

Fig. 6 is a transverse vertical sectional view through an alternative embodiment of my invention.

Referring now more particularly to the drawings, the boiler is shown as positioned in and connected with a furnace generally designated by the numeral 10. The furnace 10 comprises a front wall 11, a rear wall 12, and side walls 14 and 15 all covered by a layer 19 of insulating material. A metal floor 16, having a cover 18 of insulating material, provides a rigid support for the furnace and adapts it for marine installation. The furnace 10 is covered by a roof comprising an outer layer 13 of brick or the like, a middle section of insulating material 20 and an inner layer of tile 21.

The walls and the roof of the furnace are partially supported and are tied together by a framework comprising I beam columns 23 positioned one at each corner of the furnace. The front columns are connected at their upper ends by a transversely extending Z bar 25 and the rear columns 24 are similarly connected by a channel member 26. The columns 23 on each side of the furnace are connected by longitudinally extending I beams 24 which provide supports for an upper drum 41. The walls and the roof of the furnace are tied together by the above described steel work in such a manner as to prevent their cracking and thereby adapts the furnace for use on vessels.

The furnace is shown in Figs. 1 and 2 as equipped with an underfeed type of automatic stoker appliance which is generally designated by the numeral 27 and in which coal is fed from a hopper 33. A dump grate, comprising a plurality of sections 28 and 29, is carried by longitudinally extending I beam and channel supports 30 and 32 respectively. A pair of partition walls 31, positioned in the ash box 22, provides supports for the I beams 32. The furnace is adapted for use with all types of fuel which may be burned on a grate either through forced or natural draft.

A low partition wall 17 extends transversely of the furnace and cooperates with a baffle wall 34 to direct the gases of combustion, from the front portion of the furnace, upwardly towards the roof. The gases then travel downwardly between the baffle wall 34 and a baffle wall 35 and thence underneath the wall 35. The gases ascend between the wall 35 and the rear wall 12 of the furnace and escape past a damper 37 through an opening 38 into a flue (not shown).

The construction of the furnace and the arrangement of the boiler is in accordance with a design, intended to provide the maximum amount of water cooling surface in proportion to the volume of the furnace. The boiler proper includes a lower mud drum 40 and the upper intake drum 41 which rest upon the I beams 24. The drums 40 and 41

are connected by a plurality of vertically extending front tubes 48 and rear tubes 49. A stand pipe or vertical drum 42 is positioned in the rear of the furnace and projects above the boiler proper a sufficient distance to provide a pressure head in the boiler and to maintain all parts of the boiler constantly filled with water regardless of any listing or lurching of the vessel in which the boiler is installed. The stand pipe 42 is shown in the rear of the furnace for purposes of illustration and will perform its functions equally as well, as if positioned on one side of the furnace or in any other convenient location relative to the furnace.

The location of the drums 40, 41 and stand pipe 42, is such that the velocity of flow due to production of steam in the steaming zone automatically accelerates the circulation of the water contents of the entire boiler without any change of direction of flow in any part thereof. For this purpose the lower end of the stand pipe 42 is connected with the mud drum 40 by a water pipe 51 and the upper end of the stand pipe is connected with the top portion of the upper drum 41 by a steam discharge pipe 50.

In addition to the tubes 48 and 49, the drums 40 and 41 are connected by a system of headers and tubes forming a water cooled lining for the front and side walls and the roof of the furnace. The lining includes a pair of headers 43 oppositely positioned along the side walls 14 and 15 and preferably adjacent to the edges of the grate. The rear end of the headers 43 connect with the drum 40 and the front ends project through the furnace wall 11 where they each connect with a vertical pipe 45. The pipes 45 connect at their upper ends with a header 44 positioned on the outside of the furnace. The header 44 is connected with the drum 41 by a plurality of tubes 46 forming a water cooled lining for the front wall and the roof of the furnace. A plurality of tubes 47 connect the headers 43 with the drum 41 and form water cooled linings for the side walls 14 and 15.

The boiler is supplied with water through a feed pipe 39 opening into the top portion of the upper drum 41 and the water line is maintained in the stand pipe 42 at an elevation substantially coincident with the upper edge of the drum 41 regardless of any inclinations to which the boiler may be subjected by the rocking of the vessel. At such an elevation of the water line all parts of the boiler exposed to the gases of combustion are constantly filled with water and there is no danger of burning out any portions of the boiler or of the joints becoming loosened as is the case in boilers where there is a sudden drop of the water line leaving the upper ends of the tubes filled with only dry steam.

The cold water, fed into the drum 41 through the pipe 39, moves downwardly through the tubes 49 into the lower mud drum 40. The descending water abstracts heat from the relatively cool gases ascending between the furnace wall 12 and the baffle wall 35. Water flows from the drum 40 through the headers 43 and returns to the drum 41 through the tubes 46 and 47 forming the lining for the radiant heat zone of the furnace. Some of the water from the drum 40 also flows back to the drum 41 through the tubes 48 between and along which the relatively hot gases flow from the front portion of the furnace.

An emulsion of steam and water is produced in the tubes 46, 47 and 48 which is discharged into the upper portion of the drum 41. The emulsion thus collecting in the drum 41 flows through the pipe 50 into the space 70 above the water line in the stand pipe 42. Water flows from the lower end of the stand pipe 42 through the pipe 51 into the drum 40. The tube connections between the drums 40 and 41 and the pipe connections between the stand pipe 42 and the drums 40 and 41 are so arranged that a constant flow of water in one general direction through the boiler system results. The location of the water line in the stand pipe 42 can be ascertained by observation of a water column or gauge 64.

The stand pipe 42 provides in combination a receiver, a separator, a steam and water storage chamber, and a precipitating chamber for the removal of impurities from the water. The stand pipe 42 is the only portion of the structure in which the water line is constant since the drum 41 is partially filled with an emulsion of steam and water in a state of turbulence or ebullition.

The water storage capacity of the stand pipe 42 is dependent upon the height it projects above the boiler system and its diameter. It is desirable that the drum provide a large water storage capacity for installations in which the normal load to be carried by the boiler is heavy or is light relatively to the peak load. The steam storage capacity of the stand pipe 42 is dependent upon the diameter of the drum and its height above the water line. The storage capacity for steam provided in any particular installation will also depend upon the ratio between the peak load requirements and the normal load requirements for the boiler system.

A safety nozzle flange 52 and a steam outlet pipe 53 are both connected with the steam storage chamber 70. The steam outlet pipe 53 connects the storage space 70 with a superheater. The superheater comprises a header 57 positioned on the outside of and on one side of the furnace into which the pipe 53 discharges. A header 59 positioned on the opposite side of the furnace is connected with

the header 57 by a plurality of tubes 58 extending through the furnace transversely. The tubes 58 are so positioned in front of the baffle wall 35 that the extremely hot gases of the radiant heat zone flow between and around them. The header 59 is connected by a plurality of tubes 61 with a header 60 positioned adjacent to the header 57. The tubes 61 are so positioned underneath the tubes 58 that their steam contents abstract the heat from the descending gases in the same manner as described for the tubes 58. A baffle plate 36 tends to retard the flow of gases from between the tubes 61 and adds to the efficiency of the superheater. A main steam line 62 delivers the superheated steam into a storage reservoir or to an engine (not shown).

The emulsion of steam and water, collected in the drum 41 is discharged into the steam storage chamber 70 immediately above the water line through the release pipe 50. A novel and efficient steam separator is mounted in the steam storage chamber immediately above the water line. The separator comprises a bowl shaped head or plate 66 having a manhole opening 67 through its central portion. The plate 66 is provided with a flange 74 by means of which the plate is fastened to the drum 42. A plurality of vertically extending curved baffle plates 68 are equally spaced underneath and fastened to the plate 66 by means of flanges 69 formed on their upper ends. The outer edges of the baffles 68 are spaced away from the wall of the stand pipe to provide an unobstructed annular space between the baffles and the wall. The steam release pipe 50 discharges the emulsion into the drum 42 tangentially with a velocity of flow dependent upon the pressure generated in the drum 41, and a rotary motion of the emulsion in the annular space results. The steam contents of the emulsion will flow inwardly between the baffles 68 and ascend through the manhole opening 67 into the storage space while the water contents unites with the main body of water.

The surface friction of the tangentially flowing water coming from the pipe 50 imparts a rotary motion to the main body of water in the stand pipe 42 and thereby causes impurities in the water which are heavier than the water itself to take position at or close to the wall of the stand pipe. The boiler structure acting as a thermal pump will in regular order lower these heavy solid impurities to the bottom of the stand pipe where they can be readily drawn off through a blow pipe 55 and thereby avoid their collecting as scale in the boiler proper. The water pipe 51 which connects the lower end of the stand pipe 42 with the drum 40 has its inlet end turned upwardly in the center of the stand pipe. This arrangement minimizes the possibility that

the solid impurities which descend adjacent the wall of the stand pipe will enter the pipe 51 and thereby find their way into the boiler system proper. A blowoff pipe 56 is connected with the stand pipe 42 at or slightly below the normal water line in order that removal of impurities, lighter than water and floating upon the surface, may be easily accomplished. A blowoff pipe 54 provides means for removal of sediment from the mud drum 40.

Fig. 6 is a transverse sectional view of a boiler construction similar to that already described wherein the furnace is adapted for burning oil and the drop grate is omitted. In this construction the lower drum 40 projects through side walls 14 and 15 of the furnace and outside headers 72 are substituted for the inside headers 43. In oil burning furnaces it has been found undesirable to position the headers on the inside of the furnace for the reason that they are quickly burnt out by their intimate contact with high temperature gases of combustion.

Thus it will be seen that I have provided a boiler suitable for installation on vessels or other vehicles wherein the water line is maintained constantly at a predetermined elevation above the main boiler structure and that I have provided a novel combination of a stand pipe connected with the drums and is so positioned as to maintain the water line at a predetermined elevation above the main boiler. The stand pipe also provides an equalizer adapting the boiler for use in supplying the demands where the load is intermittently normal and suddenly increased for short periods to several times the normal, the length of time to which the boiler is subjected to abnormal loads being a governing factor in the capacity of the stand pipe. The invention also provides a novel means for separating the water and steam contents of the emulsion delivered by the boiler into the stand pipe.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a boiler system of the character described a furnace, an intake drum and a mud drum arranged within and adjacent the rear of the furnace one above the other in spaced relation, a back bank and a front bank of upstanding tubes communicating with said intake drum and mud drum, a header extending exteriorly of and adjacent the front wall of the furnace and headers arranged adjacent the sides of the fire box of the furnace providing communication between said mud

drum and the header at the front of said furnace, a bank of tubes connected to said headers adjacent said fire box and arranged so as to connect with said intake drum and thus provide a communication between the said last mentioned headers and said intake drum, a stand pipe arranged adjacent said furnace, means providing communication between said drums and said stand pipe, a fluid outlet leading from said stand pipe, and means communicating with said outlet extending through the furnace in a position whereby the fluid is superheated, and thence discharged. 70 75

2. In a boiler system of the character described, a furnace, a mud drum and an intake drum arranged above in spaced relation to said mud drum located in said furnace, a bank of tubes arranged adjacent the rear of the furnace and providing communication between said intake drum and said mud drum and a front bank of tubes being arranged within said furnace providing a communication between said drums, a header located exteriorly of and adjacent the front of said furnace, a pair of headers arranged within said furnace adjacent the sides of said fire box providing communication between said mud drum and the header located at the front of said furnace, a bank of tubes arranged in said furnace adjacent each side wall of the fire box providing communication between said intake drum and said headers located adjacent the sides of said fire box, a stand pipe associated with said furnace, means providing communication between said mud drum and said stand pipe and means providing communication between said intake drum and said stand pipe, a pair of headers arranged exteriorly of and adjacent one side of said furnace and a single header arranged exteriorly of and adjacent the other side of the furnace, means providing communication between one of the pair of headers and stand pipe, a bank of tubes adapted to super-heat the fluid leaving the stand pipe extending through said furnace providing communication between said last mentioned header and said single header, a second bank of tubes similarly arranged providing communication between said single header and the other header of said pair, and an outlet provided for the said other header. 90 95 100 105 110

3. In a boiler system of the character described a furnace, an intake drum and a mud drum transversely arranged within and adjacent the rear of the furnace one above the other in spaced relation, a pair of baffles vertically arranged in spaced relation to each other between said intake drum and said mud drum, a vertical back bank and a vertical front bank of tubes communicating with said intake drum and mud drum, said back bank being arranged between the rear wall of the furnace and one of said baffles, and said front bank of tubes being arranged between 120 125 130

- said baffles, a header located adjacent the front of the furnace and a header arranged adjacent each side of the fire box of the furnace providing communication between said mud drum and the header adjacent the front of said furnace, a bank of tubes connected to said headers adjacent said fire box and arranged to extend upwardly so as to connect with said intake drum and thus provide a communication between the said last mentioned headers and said intake drum, a stand pipe arranged adjacent said furnace, means providing communication between said mud drum and the lower interior of said stand pipe and means providing communication between said intake drum and the upper interior of said stand pipe, a pair of headers arranged adjacent one side of said furnace and a single header arranged at the other side of the furnace, means providing communication between one of the pair of headers and the stand pipe, a bank of tubes extending transversely through said furnace between said vertical back and front banks of tubes providing communication between said last mentioned header and said single header, a second bank of tubes similarly arranged through said furnace providing communication between said single header and the other header of said pair, and an outlet provided in said other header. 5
4. In a boiler system of the character described a furnace, a mud drum and an intake drum arranged above in spaced relation to said mud drum located in said furnace, a bank of tubes arranged adjacent the rear of the furnace providing communication between said intake drum and said mud drum and a front bank of tubes arranged within said furnace providing a communication between said drums, a header located exteriorly of and adjacent the front of said furnace, a pair of headers arranged within said furnace adjacent the sides of said fire box providing communication between said mud drum and the header located at the front of said furnace, a bank of tubes arranged in said furnace adjacent each side wall of the fire box providing communication between said intake drum and said headers located adjacent the sides of said fire box, a stand pipe associated with said furnace, means providing communication between said drums and said stand pipe, a pair of headers arranged exteriorly of and adjacent one side of said furnace and a single header arranged adjacent the other side of the furnace, means providing communication between one of the pair of headers and stand pipe, a bank of tubes adapted to super-heat the fluid leaving the stand pipe extending through said furnace providing communication between said last mentioned header and said single header, a second bank of tubes similarly arranged providing a communication between said single header and the other header of said pair, and an outlet provided in said other header. 10
5. In a boiler system of the character described, a furnace, an intake drum and a mud drum transversely arranged within and adjacent the rear of the furnace one above the other in spaced relation, a pair of baffles vertically arranged in spaced relation to each other between said intake drum and said mud drum, one of said baffles being arranged to depend from the ceiling of the furnace and the other extended upwardly from the floor thereof, a vertical back bank and a vertical front bank of tubes communicating with said intake drum and mud drum, said back bank being arranged between the rear wall of the furnace and one of said baffles, and said front bank of tubes being arranged between said baffles, a horizontal header extending exteriorly of and adjacent the front wall of the furnace and a pair of headers arranged adjacent the sides of the fire box of the furnace providing communication between said mud drum and the header at the front of said furnace, a bank of tubes connected to said headers adjacent said fire box and arranged to extend upwardly in a substantially vertical position from the headers adjacent the fire box and curve rearwardly so as to connect with said intake drum and thus provide a communication between the said last mentioned headers and said intake drum, a stand pipe arranged adjacent said furnace and means for maintaining the water line in said stand pipe at an elevation above the boiler system, means providing communication between said mud drum and the lower interior of said stand pipe and means providing communication between said intake drum and the upper interior of said stand pipe, means arranged in the interior of said stand pipe adjacent the means providing communication between said intake drum and stand pipe in order to provide a circuitous passage for the fluid discharged into said stand pipe, a pair of headers arranged exteriorly of and at one side of said furnace and a single header arranged exteriorly of and at the other side of the furnace, means providing communication between one of the pair of headers and the stand pipe, a bank of tubes extending transversely through said furnace between said intake drum and mud drum and between said baffles providing communication between said last mentioned header and said single header, a second bank of tubes arranged parallel to the last mentioned bank and extending through said furnace providing communication between said single header and the other header of said pair, and an outlet provided in said other header. 15
